UNITED STATES PATENT OFFICE.

JOHN E. FULLMER AND EMMETT L. BULLIS, OF KILBOURN, WISCONSIN.

PROTECTOR FOR TELEPHONES, &c.

1,178,511.

Specification of Letters Patent. Patented Apr. 11, 1916.

Application filed September 20, 1915. Serial No. 51,574.

To all whom it may concern:

Be it known that we, JOHN E. FULLMER and EMMETT L. BULLIS, citizens of the United States, residing at Kilbourn, in the county of Columbia and State of Wisconsin, have invented certain new and useful Improvements in Protectors for Telephones, &c., of which the following is a specification.

This invention relates to protectors for 10 telephone and other electrical instruments.

The object of the invention is to provide means whereby instruments of the kind referred to may positively be protected against injury to them or to their users when by 15 reason of contact of the line wires with other conductors such as electric light wires conveying a high potential current, or when during electric storms the wires are subjected to dangerous accumulations of 20 electricity, a current of such intensity or volume as to endanger burning out of the insulation resulting in short circuiting and destroying them or of injuring a user, passes over such wires.

25 A further object is to produce a protector for the specified purpose which shall be so constructed as instantaneously to ground the line wires when a current of unusual volume or intensity passes over them, and by which 30 the ground connection shall automatically cut out when such current ceases to pass over the wires.

With these objects in view, the invention consists of the device having the novel generic and specific features of construction and arrangement of parts substantially as 35 hereinafter described and claimed.

In the accompanying drawing we have 40 illustrated an embodiment of our invention which is adapted particularly for use in connection with a telephone which is in a metallic circuit, though as will be clear from an understanding of the invention it may be applied with equal facility, after slight 45 modification, to any instrument operated in connection with a grounded circuit.

In this drawing: Figure 1 is a perspective view of the protecting device; Fig. 2 is a diagrammatic view showing the electrical 50 connections when the telephone is in condition for operation; and, Fig. 3 is a diagrammatic view showing the electrical connections when the circuit is grounded between the line wires and the telephone.

55 In the usual construction of the protector

we employ a base or plate 1, which may be of any suitable material being preferably of rubber, vulcanized fiber or other non-conductor of electricity. Suitably disposed on the base are two binding posts 2, and 3, they 60 being preferably, as herein shown, arranged toward each end of the base. To the binding post 2 is attached the line wires 4 and to the post 3 is attached the line wire 5.

Arranged adjacent to the binding post 2 65 is a binding post 6, and adjacent to the binding post 3 is one 7 similar to that adjacent to the post 2. The post 2 is electrically connected to the post 6, and the post 3 is similarly connected to the post 7. Each of the 70 posts 6 and 7 have connected to them a wire 8 and each of these wires is wound upon a soft iron core 9 preferably forming two oppositely wound helices 10 and the wires are then connected to a telephone instrument 11 in a suitable way as by the binding posts 12 and 13, and the wires 14 and 15. The helices and cores are each preferably 75 covered by a water-proof coating, and are each supported by a standard 16 of non- 80 magnetic material.

In the embodiment of the invention herein shown the posts 2 and 6 and 3 and 7 are respectively electrically connected by means of plates 17 and 18 each extending beneath 85 and in contact with the posts to be so connected, and each of the plates has an upturned end terminating adjacent to a core 9. Attached to each plate at the upper end is a soft iron head 19 normally spaced from 90 the end of a core. The plates are preferably of some non-magnetic metal such as German silver. The resilient upturned ends of the plates are of such a thickness that they will hold the heads 19 away from the cores 95 against the slight attraction induced by the current of a battery ordinarily employed in the operation of the telephone.

Each of the upturned portions of the plates 17 and 18 has attached to it a projecting contact piece 20 preferably of iron, and arranged adjacent to each of such upturned portions are arms 21 of conducting material each having thereon contact pieces 22 preferably of iron which are arranged 100 oppositely to and normally separated from the contact pieces of the plates 17 and 18. The arms 21 are each electrically connected by metallic plates 23 contacting with the lower ends of such arms, and the plates are 105 110

connected to a binding post 24. To the binding post is connected one end of a wire 25 the other end of which is grounded.

The protector hereinbefore described in no way interferes under ordinary conditions with the working of the telephone with which it is incorporated, but if from any cause a current exceeding in volume or intensity that ordinarily employed passes over the line wires, the cores are instantaneously energized and the respective heads 19 drawn into contact. When this takes place the respective contact pieces 20 and 22 are brought together establishing a connection through the described parts to ground between the line wires and the telephone thus protecting the telephone or the user thereof from injury. On the discontinuance of the excess current the strength of the attraction of the cores is decreased and the resiliency of the upturned ends of the plates 17 and 18 is sufficient to remove the contact pieces 20 from those on the arms, thus automatically cutting out the ground connection and restoring the line and instrument to normal conditions.

We claim:

1. In a protective device, line wires, electromagnets connected in series with the line wires, armatures consisting of resilient plates having heads adjacent to and nor-

mally spaced from the cores of the electromagnets and connected to the line wires, contact pieces arranged on the armatures, arms having contact pieces arranged adjacent to those on the armatures and normally spaced therefrom, and connections between such arms and ground, whereby the line wires are directly connected to the ground whenever the armatures are attracted by the electromagnets. 35

2. In a protective device, line wires, an electromagnet connected with the line wires, an armature consisting of a resilient plate having a head adjacent to and normally spaced from the core of the electromagnet and connected with the line wires, a contact piece arranged on the armature, an arm having a contact piece arranged adjacent to that on the armature and normally spaced therefrom, and a connection between such arm and ground, whereby the line wires are directly connected to the ground whenever the armature is attracted by the electromagnet. 45 50 55

In testimony whereof we affix our signatures in presence of two witnesses:

JOHN E. FULLMER.
EMMETT L. BULLIS.

Witnesses:

L. N. COAPMAN,
O. P. HELLAND.
